UNITED STATES PATENT OFFICE.

EDGAR FULTON CROWTHER, OF VICKSBURG, MISSISSIPPI.

AIR HEATING AND DISTRIBUTING APPARATUS FOR OPEN FIREPLACES.

SPECIFICATION forming part of Letters Patent No. 669,912, dated March 12, 1901.

Application filed May 8, 1900. Serial No. 15,387. (No model.)

To all whom it may concern:

Be it known that I, EDGAR FULTON CROWTHER, a citizen of the United States, residing at Vicksburg, in the county of Warren and State of Mississippi, have invented new and useful Improvements in Air Heating and Distributing Apparatus for Open Fireplaces, of which the following is a specification.

My invention relates to air heating and distributing apparatus for open fireplaces, my purpose being to provide such a construction and combination of parts that a large volume of superheated air may be put in rapid circulation and distributed to a number of different points, the apparatus by which this is accomplished being so arranged in and combined with an open fireplace as to occupy scarcely any of the available space of the fireplace or open grate and so placed and of such material as to communicate heat to the air almost as soon as the fire is started.

It is my purpose also to provide an air heater and distributor by which the air will be raised to a high temperature and discharged at the points where its heat is utilized without material loss.

It is my object also to provide such apparatus with simple and novel means for impregnating the heated air with a suitable degree of moisture to render its inspiration pleasant and healthful, and in this connection I also provide improved means for renewing the supply of water used for this purpose.

It is my aim to provide an air-heating apparatus for open fireplaces or open grates which can be readily and quickly set therein without any special changes in construction, which will not cause any noticeable change in the appearance of an ordinary fireplace nor obstruct or crowd the same, and which will utilize the heat of the fire to the highest possible degree in quickly heating the inflowing air to a very high point and maintaining it at a practical uniform temperature.

My invention also comprises the useful and novel features, all of which will be fully explained in the following specification and then particularly pointed out and defined in the claims at the close thereof.

For the purpose of the following descrip-

tion reference is had to the accompanying drawings, in which—

Figure 1 is a front elevation, partly in section, of a fireplace or open grate equipped with my invention. Fig. 2 is a vertical section of the same, taken substantially in the center of the grate. Fig. 3 is a side elevation of the same, the chimney structure being mostly omitted. Fig. 4 is a plan view, the left-hand part of said figure being in section. Fig. 5 is a detail section of one of the side boxes. Fig. 6 is a front elevation showing the several parts of the apparatus in correct relative position, but slightly separated from each other to more clearly illustrate their construction.

The reference-numeral 1 in said drawings indicates the receiver, to which fresh pure air is supplied from any suitable source through a pipe 2, part of which only is shown in the drawings. The receiver is constructed to lie beneath the grate-bars 3 and somewhat behind them and is provided with a central opening 4, with which the intake connection 7c or fresh-air pipe 2 communicates. Along the front of said receiver 1 is a trough 5, which serves as a water-reservoir, its supply being renewed in the manner hereinafter explained.

At each end or side of the fireplace is a side box 6, which receives air from the chamber 1 through passages 7 at the ends of said chamber. These side boxes are each formed of three or more tubular sections 8, (shown in Fig. 5,) with recessed webs 9 connecting them, the chambers in said webs opening into said tubular sections. The side boxes extend from the top of the receiver, at the ends of the latter, nearly or quite to the top of the fireplace, their upper portions being inclined 90 rearward and upward, as seen in Fig. 3, until both front and rearward tubular sections unite at their tops in a coupling 10. This coupling enters the ports 12 at the ends of a distributor 13, which lies at the upper part 95 of the open fireplace, its central uptake 14 passing into the mouth of the smoke-flue 15, as shown in Fig. 2. From the middle of the distributor is a forwardly-projecting portion 16, forming a chamber which is part of the distributor-chamber. The lower wall of said projection is provided with tubular projections

or thimbles 17, into which the ends of a series of pipes 18 are inserted. These pipes, four of which are shown in this instance, lie in a single row at right angles to the receiver and distributor, their lower ends being set around nipples 19, which rise from the upper wall of a central forward projection 20 on the receiver. To increase the heating-surface, a row of pipes 21 is arranged along the back of the fireplace, their ends opening into both receiver and distributor, to which they are coupled by a construction similar to that used for the ends of the pipes 18. I may also use one or more pipes 22 on each side of the central rank of pipes 18. The distributor and the upper ends of all these pipes are concealed from view by the front 23. All these pipes have a slight inclination toward the front, and being placed against the back and center they receive the maximum heat of the grate. Being formed of thin wrought-iron, which conducts heat far more readily than cast-iron, they begin to furnish hot air to the distributor almost as soon as the fire in the grate or fireplace is under way. It will be noted also that narrow intervals or draft-spaces are provided between the pipes and between the latter and the rear wall of the fireplace. These spaces furnish ample room for draft, and the smoke, hot gases, and other products of combustion pass around them and in contact with their entire surface. The distributor and end boxes, on the other hand, are of cast-iron, which absorbs heat more slowly, but retains it longer, and being placed in the middle of the flue it is heated on all sides as well as by the hot air coming from the pipes. I make the distributing-pipe 14 of less diameter than the intake 2, my object being to hold the entering volume of air in the heating-tubes until it acquires as high a temperature as possible, its expansion causing it to flow slowly through the thin wrought-iron pipes, thereby taking up far more heat than it could if it flowed at a higher speed. When the distributor has acquired its maximum heat from both exterior and interior sources, the air entering it from the heater-pipes will be raised to the highest temperature possible, considering the condition of the fire in the grate, and it will pass through the distributing-pipes to the points where its heat is utilized without any great reduction. Suitable registers and valves will be provided at these points to control the volume of air entering.

Water is supplied to the trough or reservoir 5, which may communicate at each end with a much larger chamber 5^a, by merely raising one of the central series of pipes 18 off its nipple 19, thereby causing its upper end to pass into the central projection 16 on the distributor, whereupon water can be supplied by means of a tunnel inserted in the open nipple.

The side boxes are fitted over each end of the receiver, and their upper ends are fitted into the ends of the distributor, which have a downward projection. All the heater-pipes are inserted at their upper ends into short thimbles 24 on the lower face of the distributor, and their lower ends are set on and around nipples 25 on the upper face of the receiver, the construction being similar to that described in connection with the pipes 18. They can all be readily removed by slipping them into the distributor far enough to enable their lower ends to be unseated from the nipples 25.

Having thus described my invention, what I claim as new, and desire to secure by Letters Patent of the United States, is—

1. In an air-heater for open fireplaces, or grates, the combination with a receiving-chamber beneath and partly behind the grate-bars, of a distributor in the upper part of the fireplace, heating-pipes of thin wrought-iron connecting said receiver and distributor, and a central series of heating-pipes transverse to the others, their ends opening into central projections on the receiver and distributor, substantially as described.

2. In an air-heater for open fireplaces and grates, the combination with a receiver lying beneath and partly behind the grate-bars, of a distributor in the upper part of the fireplace, side boxes consisting of tubular sections connected by recessed webs, the upper ends of said sections inclining rearwardly and entering hanging couplings on the end of the distributor, and their lower ends communicating with the ends of the receiver, and a series of heating-pipes arranged along the rear of the fireplace and having a forward inclination, their upper ends entering thimbles on the distributor and their lower ends seating around nipples on the receiver, substantially as described.

3. In an air-heater for open fireplaces, or grates, the combination with a receiver arranged beneath the grate-bars and having a trough or water-reservoir along its front side, communicating at its ends with larger reservoirs in the ends of the receiver, of a distributor in the upper part of the fireplace, heating-pipes arranged along the back and connecting the receiver and distributor, and a central transverse row of pipes communicating with central projections on the front of said receiver and distributor, one of which pipes is capable of displacement to enable the water-supply to be renewed, substantially as described.

In testimony whereof I have hereunto set my hand in presence of two subscribing witnesses.

EDGAR FULTON CROWTHER.
